[57] CLAIM

The ornamental designs for wall mounted modular tray, as shown and described.

DESCRIPTION

FIG. 1 is a perspective view of a wall mounted modular tray showing my new design;

FIG. 2 is a top plan view of FIG. 1;

FIG. 3 is a side elevational view of FIG. 1;

FIG. 4 is a rear elevational view of FIG. 1;

FIG. 5 is a front elevational view of FIG. 1;

FIG. 6 is a bottom plan view of FIG. 1;

FIG. 7 is a sectional view taken on line 7—7 of FIG. 2;

and

FIG. 8 is a perspective view of a second embodiment of the design of FIG. 1, the only differences residing in the depth of the depression, its division into two sections and the width of the tray.
